[57] CLAIM

The ornamental design for a tool for opening containers, as shown and described.

DESCRIPTION

FIG. 1 is a perspective view of a tool for opening containers, showing our new design;

FIG. 2 is a side elevational view thereof;

FIG. 3 is a top plan view thereof;

FIG. 4 is a bottom plan view thereof, a portion of the strap being broken away for clarity;

FIG. 5 is a view similar to FIG. 2 showing the opposite side thereof;

FIG. 6 is an end elevational view thereof from the left of FIG. 2; and,

FIG. 7 is an end elevational view thereof from the right of FIG. 2.

FIG. 1

FIG. 2

FIG. 3

FIG. 4

FIG. 5

FIG. 6

FIG. 7
